(57) CLAIM

The ornamental design for an inflatable bear costume, as shown and described.

DESCRIPTION

FIG. 1 is a front perspective view of an inflatable bear costume, showing our new design;

FIG. 2 is a right side perspective view thereof;

FIG. 3 is a left side perspective view thereof;

FIG. 4 is a back perspective view thereof; and,

FIG. 5 is a front and left side perspective view thereof.

The broken lines illustrate portions of the inflatable bear costume that form no part of the claimed design.

1 Claim, 5 Drawing Sheets
